No. 12,827

MARCH 21, 1882

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 12,827, dated March 21, 1882.

Application filed February 11, 1882. Term of patent 3½ years.

To all whom it may concern:

Be it known that I, HENRY HUNT, of Greenville, in the county of Hudson and State of New Jersey, have invented a new and original 5 Design for Carpets, of which the following is a specification.

This invention relates to a new and original design for carpets and similar fabrics; and it consists in the novel grouping and configuration 10 of figures hereinafter more fully described.

The accompanying photograph illustrates a face view of a carpet having my new design.

A is an irregularly-shaped panel, convex above and bounded by the ornamental border stripes 15 *a* and *b*. Traversing the panel *A*, and projecting out over portions of the borders *a* and *b*, is the flower cluster *B*, consisting of roses and small flowers and leaf groups arranged along a forking stem that springs from the left lower corner of *A* and extends irregularly over it. To the right of *A* is the right-lined panel *C*, shown in part on each side of the photograph, long and narrow in form, and with a V shape 20 in its lower bounding-line. Above it is the border *c*, with a small geometric ornament partially concealing *a* on the left, and being itself concealed by other figures on the right. Below *C* is the border *d*—a stripe ornamented by square figures above damask pendants—and border *e*—a stripe with circular figures. *C* is 25 traversed by the group of flowers and leaves *D*. Above *A* and to the right is the square panel *E*, concealed below by *A* and *C* and the borders *a* and *c*, bounded by the border *f*, ornamented by square figures, and on the right by the border *g*, ornamented by small circular and rectangular figures, the border *f* being concealed by other figures. *E* is ornamented by alternate small square and circular figures, 30 and is traversed by a flower-and-leaf cluster, *F*. *G* is an irregularly-shaped panel partly concealed by adjacent figures. It is bounded above by the border *e* and ornamented by small arch-like figures. It is traversed by the flower 35 group *H*, consisting of two large flowers with spreading petals and smaller flowers or buds and leaves. Below *G* and to the left of *A* is the panel *K*, somewhat resembling a quarter of a hexagon in shape. It is bounded by the

border *g* above and to the left and by the serrated border *h* on the right. It is traversed by the group *L*, consisting of a vase-like figure at the base, from which springs a cluster of leaves and bulb-like flowers. Below *A* and *C* and to the right of *K* is the irregular panel 50 *M*, shown in part at each end of the photograph. At the left lower corner *M* is ornamented by an irregular serrated figure, *k*. A portion of *M* above *k* is ornamented by a group, *n*, of small figures resembling interlocking 55 arches. At the right lower corner *M* is ornamented by the figure *l*—a wreath of leaves encircling a leaf cluster. Above *M* is traversed by the group *m* of spreading leaves and scroll forms and bounded by the wide border *d*. 60

The whole design presents the appearance of a number of variously shaped and ornamented panels irregularly overlapping one another.

I claim—

1. The design for carpets, consisting of the panel *A*, traversed by the group *B* and bordered by *a* and *b*, substantially as shown.

2. The design for carpets, consisting of the panel *C*, traversed by the group *D* and bordered by *e* and *d*, substantially as shown. 75

3. The design for carpets, consisting of the ornamented panel *E*, traversed by the group *F* and bordered by *f*, substantially as shown.

4. The design for carpets, consisting of the ornamented panel *G*, traversed by the group *H* and bordered by *e*, substantially as shown.

5. The design for carpets, consisting of the panel *K*, traversed by the group *L* and bordered by *g* and *h*, substantially as shown. 85

6. The design for carpets, consisting of the panel *M*, ornamented by the figures *k*, *l*, *m*, and *n* and bordered by *d*, substantially as shown.

7. The design for carpets, consisting of the panels, groups, and figures *A*, *B*, *C*, *D*, *E*, *F*, *G*, *H*, *K*, *L*, *M*, *a*, *b*, *c*, *d*, *e*, *f*, *g*, *h*, *k*, *l*, *m*, and *n*, substantially as shown. 90

HENRY HUNT.
